UNITED STATES PATENT OFFICE.

WILLIAM E. WINE, OF TOLEDO, OHIO.

CAR-DOOR-LOCKING DEVICE.

REISSUED

Application filed January 12, 1922, Serial No. 528,649.

To all whom it may concern:

Be it known that I, WILLIAM E. WINE, a citizen of the United States of America, residing at Toledo, in the county of Lucas and 5 State of Ohio, have invented certain new and useful Improvements in Car-Door-Locking Devices, of which the following is a specification.

My invention relates to new and useful 10 improvements in car door locks and has for an object to provide a lock comprising a bracket or base plate, which is designed to be secured to the side of a freight car, and on which bracket is eccentrically mounted a 15 hook which in turn is designed to support a drop bottom door; first, in a partly open position and, from which point, the hook will be raised to force the door to its final and locked position where it will remain until the hook is manually operated to release 20 the door.

As is well known to those skilled in the art, drop bottom doors are easily handled or manipulated with the exception of the final 25 closing and locking movement, as often times the doors become distorted or warped in service or small particles of coal or other substance jam along the sides or hinged edge of the door and it is necessary to exert great 30 force to raise the door the last few inches.

Another object of the invention, therefore, is to provide a hook which cooperates with a transversely mounted angle on the door to support the door in its nearly closed position, and to have this hook eccentrically 35 mounted so that a wrench may be placed on the eccentric mounting of the hook so that the hook may then be swung beyond the lower pivotal axis which will raise the hook 40 and door and lock the door in its closed position.

Still another object of the invention is to provide a locking arrangement consisting of a bracket on which is eccentrically mounted 45 a hook and behind which is mounted a dog to further hold the hook in its closed position so that it will be impossible for the hook to open unless the hook is manually manipulated.

50 Still another object of the invention is to provide a locking means for drop bottom doors which will consist of but few parts, relatively strong, easily operated and relatively cheap to manufacture.

55 With these and other objects in view my invention consists in certain new and novel

construction and combination of parts as will hereinafter be more fully described and pointed out in detail in the claims.

Referring now to the drawings showing a 60 preferred embodiment of the invention,

Fig. 1 is a side elevation of the locking device, a fragmentary portion of the side of a car being shown and one edge of a drop bottom door, the door being in its closed 65 and locked position.

Fig. 2 is a similar view, the door in this instance, being shown in a temporary partly closed position, the lock being swung to its open position.

70 Fig. 3 is a detailed sectional view taken on line 3—3 of Fig. 1, and

Fig. 4 is a sectional view taken on line 4—4 of Fig. 1.

In the drawings, a fragmentary portion 75 1 of the side of a car is shown, a bracket 2 which is secured to a center sill (not shown) to which bracket is hinged the door 3 and across and beyond which extends an angle iron 4 to provide a supporting ledge on the 80 door 3 which rests on the supporting ledge 5 of a hook 6, while the door is in its locked position.

Referring now, more particularly to the locking device, there will be seen a plate or 85 bracket 7 which is substantially triangular in shape and is secured by three rivets 8 to the side of the car 1, a plate 9 being placed behind the bracket and side of the car 1 through which are also passed the rivets, 90 the plate forming a reinforcement so that the bracket and hook will not be torn from its position.

This base plate or bracket 7 is provided with three integral outstanding bearing 95 posts 10, 11 and 12 which are drilled for the reception of the aforesaid rivets 8, and on two of which bearing posts are mounted the hook 6 and dog 13 respectively, while the lower bearing post 11 forms a stop for the 100 inward movement of the hook 6. A strap 14 is secured on the outer ends of the two posts 11 and 12 and is held by two of the rivets 8, which strap prevents transverse movement of the hook 6 and the dog 13. 105

Referring now more particularly to the upper portion of the hook 6 and the manner in which it is mounted, it will be seen that it comprises an enlarged head 15 provided with the opening 16 in which rotatably fits 110 the circular hub 17 which is provided with the opening 18 at a point distant from the

center thereof. It will be noticed that the hub 17 is slightly reduced as at 19 so that although the hook 6 may pivot on this hub the flange formed by the reduced portion 19 5 will prevent any looseness or transverse movement of the head 15 on the hub 17.

It will be seen that when the hub and hook are swung to the position shown in Figs. 1 and 3 the hook will be held in its uppermost 10 and locked position and will remain in this position as the pull will be to one side of the lower pivotal axis. The hub 17 is of sufficient width to provide a bearing surface for a wrench so that the eccentrically mounted hook may be easily swung to its open or 15 closed position.

Supposing the door is open, the dog 13 will have been thrown back to the position shown in Fig. 2 and the door will then be 20 raised by hand to a temporary supporting position as shown in Fig. 2 so that the angle iron will rest on the ledge 5 of the hook 6. The hub 17 may then be grasped by a wrench and revolved to the position shown in Figs. 25 1 and 3 which will exert great force on the door, pulling it to its uppermost position and holding the same against accidental opening, this of course, due to the eccentric mounting of the hooks. After which the 30 dog will be swung over as also shown in Fig. 1 to further provide against any accidental disengagement of the hook and the angle 4 on the bottom of the door.

The hook and the plate may be flanged to 35 provide great strength and relative lightness in weight as shown in the several figures, although, of course, this is not absolutely necessary.

From the foregoing it will be seen that I 40 have provided a locking device which is exceedingly simple in construction, compact in nature, relatively strong and easy to operate. Due to the eccentric mounting of the hook, the door may be supported in a 45 temporary position and by the use of a wrench sufficient force may be exerted to swing the hook to its final position which will raise the door and securely lock the same in its closed position.

50 Many slight changes may be made without in any way departing from the spirit and scope of the invention.

What I claim as new and desire to secure by Letters Patent is:—

55 1. A locking device for car doors comprising a base, bearing posts formed on said base, a hook having an enlarged head eccentrically mounted on one of said bearing posts, and said hook adapted to support and 60 lock a door in its closed position when said hook is revolved to its locked position.

2. A locking device for car doors comprising a base, said base provided with a bearing post, a hook having an enlarged head 65 thereon, a hub within said head, and said

hub eccentrically mounted on said bearing post, said hook adapted to engage and support a door when in one position and when revolved to raise the door to its final position and support and lock the same in said 70 position.

3. A locking device for car doors comprising a base plate provided with bearing posts thereon, a hook having an enlarged circular head formed with an opening therein, a hub within said head, said hub eccentrically mounted on one of said bearing posts, a strap extending from two of said posts and a dog pivotally mounted on one of said bearing posts to further retain the hook in its 80 final position.

4. In combination with a freight car, having a swinging door, a locking device secured to the car body, said door provided with an outwardly extending ledge, said locking device comprising a base plate secured to the sides of the car body, bearing posts formed on said plate, a hook provided with an enlarged head and having an opening therein, a hub within said opening in said head and 90 said hub mounted on one of said bearing posts and eccentric therewith, the lower end of said hook adapted to engage the ledge on said door to support the same in a temporary position and the upper end of said hook 95 adapted to be revolved so that said door will be raised and locked in its closed position.

5. In combination with a car body, having a drop door, provided with an outwardly 100 extending ledge, a locking device comprising a base secured to the side of the car body and near the free edge of said door, said base provided with integral bearing posts formed thereon, a hook provided with 105 an enlarged head having an opening therein and a hub rotatably mounted in said opening, said hub extending outwardly beyond the head of said hook to present an engaging surface for revolving said hook, said hook when in its lowermost position engaging the said outwardly extending ledge on said door to support the door in a partly closed position and said hook raising and locking the door when the hub is revolved to 110 a point beyond the lower pivotal axis of said hook.

6. In combination with a freight car having a drop bottom door provided with a ledge in the form of an angle iron, extending beyond the free edge of the same, a locking device comprising a base plate rigidly secured to the side of the car and above the angle iron secured to the door, bearing posts formed on said base plate, a hook having an enlarged head provided with an opening therein, a hub fitting within said opening and eccentrically mounted on the uppermost of said bearing posts, a dog pivotally mounted on the rearmost of said bearing posts, a 130-

strap extending between said rearmost bearing post and the lowermost bearing post, said hook adapted to engage the angle on said door and support the door in a partly 5 open position and to raise and lock said door in its closed position when the hub is revolved.

7. In combination with a car having a drop bottom door provided with a ledge extending beyond the free edge thereof, a locking device comprising a triangular base plate secured to the car body, and above said ledge, bearing posts formed on said base plate, a hook having an enlarged head provided with an opening therein, a rotatable hub in said opening eccentrically mounted on the uppermost of said bearing posts, said hub having two flat sides to present a gripping surface, a strap extending between two 10 of said posts to prevent transverse movement of said hook, said hook when lowered by the revolving of said hub engaging the ledge on said door and supporting the same in a partly closed position and raising and 15 locking the door when said hub is revolved, and means mounted on the rearmost bearing post for further holding the eccentrically mounted hook in its locked position.

8. In combination with a car having a drop door provided with a ledge extending 20 beyond the side thereof, a locking device

comprising a base plate rigidly secured to the car body and above the ledge on the car door, bearing posts formed on said base and a hook eccentrically mounted on one of said bearing posts, said eccentric mounting comprising means for supporting the upper end of said hook and allowing the same to be swung to one side of the lower pivotal axis, said means also presenting a surface to be 25 engaged by an instrument for manually swinging the upper end of said hook; said hook supporting the door in a partly closed position when said hook is in its lowermost position and raising and locking the door 30 in a closed position when the hook is swung to its opposite position.

9. In a door arrangement for railroad cars, a door hinged to the car body, a bracket carried by the car, a door supporting member 35 pivotally associated with the door and in said bracket and arranged for engagement with a portion of the door, the bracket having a circular aperture therein, the door supporting member comprising in part a 40 spool rotatably mounted in the aperture, the pivotal point of the said door supporting member being upon the said spool and slightly removed from the axis of rotation 45 thereof.

In testimony whereof I affix my signature.
WILLIAM E. WINE.
